(57) **CLAIM**

The ornamental design for a trap for rodents, as shown and described.

DESCRIPTION

FIG. 1 is a perspective view;

FIG. 2 is a top view thereof;

FIG. 3 is a front elevational view thereof;

FIG. 4 is a side elevational view thereof;

FIG. 5 is a bottom view thereof;

FIG. 6 is a rear view thereof;

FIG. 7 is a perspective view thereof with the lid removed;

FIG. 8 is a perspective view of an alternate embodiment thereof;

FIG. 9 is a top view of an alternate embodiment thereof;

FIG. 10 is a side elevational view of an alternate embodiment thereof;

FIG. 11 is a bottom view of an alternate embodiment thereof;

FIG. 12 is a front elevational view of an alternate embodiment thereof; and,

FIG. 13 is a perspective view of an alternate embodiment thereof with the lid removed.

The broken line showing of environment in FIGS. 7 and 13 is included for the purpose of illustrating only and forms no part of the claimed design.
